BOOK SUPPORTER

Leon Zocchi, Milford, Mass.

Application December 23, 1935, Serial No. 55,741

5 Claims. (Cl. 45—57)

This invention relates to a device for supporting a book in an inclined position on a table or desk. It is an object of the invention to provide a book stand which is compact in structure so as 5 to be capable of being carried in a pocket, which is simple and cheap, and which is effective in operation.

The invention as herein described comprises two members, a base and an upright, the upright 10 being preferably in the form of a cylindrical rod which is movable from a nested position within the base to a position for use in which it is supported inclined at a suitable angle to the base. When in use, the rod is inserted between the 15 back of the book and the central portion of the binding.

For a more complete understanding of the invention, reference may be had to the description thereof which follows and to the illustration of an 20 embodiment thereof on the drawing of which

Figure 1 is a perspective view of the device embodying the invention, showing a book in place thereon.

Figure 2 is a front elevation of the same.

Figure 3 is a plan view of the device in collapsed form.

Figures 4, 5 and 6 are fragmentary sectional views of a portion of the device showing the rod in different positions.

The device consists essentially of two members, 30 a base 10 and a rod 12. The base is preferably elongated for stability and is provided with a flat bottom or with spaced edge portions in a common plane. As shown, the base member 10 is in the 35 form of a housing consisting of a flat bottom 14 with a non-skid surface and an upper channel member 16 secured along its margins to the bottom plate 14, so that the structure of the housing 10 is substantially integral. Near one end of the 40 channel member 16 is a short slot 20. Through this slot projects a rod 22 which preferably is circular in cross section. The lower or inner end of the rod is enlarged as at 24, this portion of the rod being wider than the slot 20 so that complete removal of the rod from the housing is thus 45 prevented. The rod 22 is readily slideable in the slot 20 from the position illustrated in Figure 3 to an extended position wherein the enlarged portion 24 engages the sides of the slot 20. When 50 the rod has thus been drawn out as far as possible, it may be swung through an upright position to an inclined position overhanging the base 10. It is then in position for use and a hook may be inserted on the rod in such a way that the 55 rod extends through the space between the cen-

tral portion of the binding and the back of the book where the signatures are sewed together, as illustrated in Figure 1. The book is then supported by the rod in a convenient position for reading, the rod being capable of supporting the 5 book when the latter is either open or shut. The book is readily removable from the rod and the device can then be collapsed to the position shown in Figure 3, whereupon it can be slipped into a pocket.

If desired, the rod can be supported at a plurality of angles of inclination, as indicated in Figures 4, 5 and 6. To this end, the sides of the slot 20 may be serrated or notched so that the enlarged portion 24 of the rod may engage selectively in any pair of notches. The rod itself may also be grooved as at 30, these grooves selectively engaging the end 32 of the slot 20 to cooperate with the enlarged end 24 in supporting the rod in one or another of its positions for use.

It is evident that various modifications and changes may be made in the embodiment herein shown and described without departing from the spirit or scope of the invention as defined in the following claims.

I claim:—

1. A book stand comprising an elongated hollow base having a short slot near an end thereof, a substantially cylindrical rod freely slideable through said slot, said rod having an enlarged 30 portion adjacent to its inner end adapted to cooperate with the sides of the slot to support the rod in an inclined position overhanging said base when the rod is pulled out of said base for cooperation with said portion.

2. A book stand comprising an elongated base including an inverted channel member with a short slot in an end portion thereof, a rod slideable through said slot from a nested position in said channel to a position for use in which said 40 rod extends upwardly from said slot and is inclined to overhang said base, said rod having an enlarged end portion cooperating with the sides of the slot to support said rod in its position for use.

3. A book stand comprising a hollow base in the form of an elongated flat-bottom housing having a short slot adjacent to an end thereof, and a rod slideable longitudinally through said slot into enclosed position in said housing, said rod having an enlarged portion wider than the slot 50 adjacent to its innermost end and adapted to cooperate with the sides of the slot to support the rod in an inclined position over the base when 55

the rod is pulled out of said base for cooperation with said portion.

4. A book stand comprising an elongated hollow base with a short slot near the forward end thereof, a rod having a substantially circular cross section adapted to slide longitudinally through said slot, said rod having a enlarged inner end portion adapted to engage the sides of the slot to support said rod at predetermined 10 angles of rearward inclination over the base when said rod is pulled out and swung back so that its inner end portion cooperates with the sides of said slot.

5. A book stand comprising a base having a short slot in an end portion thereof, and a rod 5 slidable through said slot, said rod having an enlarged end portion wider than the slot and peripheral grooves adjacent to said enlarged end portion, said grooves selectively engaging an end of the slot and cooperating with said enlarged portion of the rod and the sides of the slot to support said rod selectively in any one of a plurality of inclined positions overhanging said base. 10
